Charles R. Searle.

UNITED STATES PATENT OFFICE.

LOUIS BLOCK, OF MAMARONECK, NEW YORK.

METHOD OF COMPRESSING GASES.

1,425,938.

Specification of Letters Patent. Patented Aug. 15, 1922.

Application filed March 13, 1918. Serial No. 222,066.

To all whom it may concern:

Be it known that I, LOUIS BLOCK, a citizen of the United States, residing at Mamaroneck, in the county of Westchester and State of New York, have invented a certain new and useful Method of Compressing Gases, of which the following is a specification.

The invention relates to the liquefaction of gases by compression, and is intended more particularly for the treatment of chlorine gas in a reciprocating compressor.

The object of the invention primarily is to remove the moisture or vapor of water from the gas by exposing it in the compressor to the absorbent action of sulphuric acid.

A further object is to supply the acid without lessening the charge of gas received in the compressor cylinder, and to introduce the acid at a pressure above that of the gas entering the compressor.

Another important object is to prevent the entrance of moisture from the atmosphere to the compressor through the stuffing-box and to arrest such moisture carried by the piston-rod.

Another important object is to supply the acid to the compressor at a relatively low temperature, thereby aiding in absorbing the heat of compression developed in the gas.

The accompanying drawings form a part of this specification and show an apparatus designed for successfully carrying out the improved method.

Figure 1 is a side view of a single acting compressor and its connected parts, adapted for this purpose.

Figure 2 is a corresponding front view with certain parts omitted.

Figure 3 is a diametrical section through the upper or delivery end of the compressor, on a larger scale, showing one of the delivery valves in elevation.

Figure 4 is a similar section through the lower end of the compressor cylinder, the stuffing-box, and piston.

Figure 5 is a vertical section through the intake valve and its immediately connected parts.

Figure 6 is a vertical diametrical section through the separating tank, with certain portions shown in elevation.

Similar letters of reference indicate the same parts in all the figures.

A is the cylinder of a single acting compressor; A¹ the upper head, A² the lower

head, and A³ the stuffing-box thereon. A⁴ is the intake connection, A⁵ the delivery connection, and B the piston having a piston-rod B² connected to the crosshead C and reciprocated through a connecting-rod C¹ by a crank C² on the shaft C³ mounted in suitable bearings in the frame of the compressor and driven by a pulley C⁴.

At the upper end of the cylinder is a drum D seated on an annular valve seat D² below the delivery orifice A⁵ and held normally to such seat by a set-screw D³ extending through the upper head and impinging upon the upper face of a breaking-plate D⁴ mounted on a tubular support D⁵ which rests upon the upper face of the drum. In the latter are a number of upwardly opening valves D¹ mounted in casings D⁶, only one of which is shown.

The piston B is chambered as shown and carries an upwardly opening valve B¹ the gravity of which is nearly balanced by a slight supporting spring B³ carried by the piston beneath the valve. Below the piston B is the inlet connection A⁴ to which is joined a casing E containing a light intake valve E¹ held to its seat E² by a spring E³; and to the intake connection below the valve E¹, is secured a chamber F containing a conical strainer F¹, and having a nozzle F² to which is joined a pipe, not shown, leading from the supply of the gas to be treated and compressed.

G is a separating tank shown as mounted vertically on the frame of the compressor at the rear; it is adapted to contain a supply of sulphuric acid in its lower end, the depth of which may be read on a gauge-glass G². In the lower end of the separating tank and bathed in the acid, is a coil H of pipe the ends of which extend through the head G¹ of the tank and serve to permit a circulation of cooling water through the coil.

From the delivery connection A⁵ extends a pipe J, passing downwardly through the head G¹ of the tank and terminating above the normal level of the acid therein, and J¹ is an outlet pipe secured to the head G¹ and leading to a suitable reservoir or container, not shown, for further separating the gas from the sulphuric acid.

At the bottom of the separating tank are valves and connections, as at G³, through which the vitiated acid in the tank may be drawn off and a new supply introduced, and L is a pipe leading from a low point in the

tank, upwardly to the stuffing-box A³, adapted to carry acid to a lantern-gland L¹ surrounding the piston-rod and held in proper relation to the supply orifice from the pipe L by packing, not shown, in the stuffing-box. On the opposite face of the latter is a corresponding orifice through which the acid passes after filling the interior of the lantern-gland, and by a pipe L² is led to the interior of the compressor cylinder immediately above the lower head A².

M is a cock by which the flow of acid through the pipe L to the lantern-gland and cylinder may be controlled and regulated, and is preferably of the rotatable plug type, as best adapted to resist the action of the acid for long periods.

The apparatus above described operates as follows in carrying out the improved method:—At each upstroke of the piston B the partial vacuum thus produced causes an inflow of gas below the piston, through the strainer F¹, which arrests any particles of matter held mechanically suspended in the gas, past the intake valve E¹ and fills the cylinder. The succeeding down stroke transfers the charge of gas through the lightly supported piston valve B¹ to the cylinder above the piston. The next upstroke of the piston draws in a fresh charge and compresses the contained charge to the liquefying pressure, and forces it through the valves D¹ in the drum D, and pipe J, to the separating tank G where it is discharged. The chlorine gas fills the upper portion of the tank, finally escaping through the pipe J¹ to a reservoir.

It will be noted that the separating tank is under the pressure of the compressed gas which forces the acid in the lower portion thereof in quantities permitted by the pipe L and valve M to the interior of the lantern-gland L¹ and completely incloses the piston-rod in the stuffing-box A³ in a bath of acid under pressure which effectually prevents any leakage into the stuffing-box, and by its affinity for water absorbs any moisture entering the stuffing-box or carried thereto by the movements of the piston-rod. From the opposite side of the stuffing-box the pipe L² leads the acid to the interior of the cylinder A and forms a layer on the lower head A² held by the intake valve E¹, which may fill the space below the piston B. The suction caused by the upstroke of the piston will lift the valve E¹ and draw such acid mingled with the inrushing gas into the cylinder until at or near the completion of the upstroke, the valve E¹ again closes. The suction due to the upstroke prevents any escape of acid to the chamber F while the valve E¹ is open.

At each transfer of the gas through the piston on the down-stroke of the latter, a small quantity of acid is also transferred

and lies in a layer on the upper face of the piston and its valve B¹, and is delivered with the compressed gas through the valves D¹ and pipe J to the separating tank. In this traverse the gas and acid are intimately mingled, with the result that practically all the moisture in the gas is absorbed by the acid.

The acid is cooled in the separating tank G by the circulation of the cooling water through the coil H and is delivered to the stuffing-box and cylinder at a comparatively low temperature, so that in addition to absorbing the water in the gas, it performs the further useful function of aiding in absorbing the heat of compression.

The corrosive action of sulphuric acid is slight when undiluted with water, but increases as water is added, so that it is important to re-charge with pure acid at intervals more or less frequent as conditions may require; this is effected by means of the valves and connections G³.

By mounting the delivery valves D¹ in the drum D, and holding the latter to its seat by the breaking-plate D⁴ and set-screw D⁵, serious damage to the compressor, due to accidental failure of the valves D¹ to permit the escape of acid and compressed gas with sufficient rapidity, is avoided and the only effect of such condition is to break the plate D⁴ and permit the drum D to lift and relieve the pressure.

I claim:—

1. The method described of treating gas by circulating sulphuric acid through the gas for absorbing moisture in the gas, consisting of delivering such acid to a compressor prior to its entrance to the compressing zone, transferring such acid to such zone after the transfer of the charge of gas to such zone, compressing such charge of gas in the presence of such acid, and delivering such acid with the compressed gas.

2. The method described of treating gas by circulating sulphuric acid through the gas for absorbing moisture in the gas, consisting of delivering such acid to a compressor prior to its entrance to the compressing zone, sealing the stuffing-box of said compressor; transferring such acid to such zone after the transfer of the charge of gas to such zone, compressing such charge of gas in the presence of such acid, and delivering such acid with the compressed gas.

3. The method described of treating gas by circulating sulphuric acid through the gas for absorbing moisture in the gas, consisting of delivering such acid to a compressor prior to its entrance to the compressing zone, sealing the stuffing-box of said compressor with such acid, transferring such acid to such zone after the transfer of the charge of gas to such zone, compressing such charge of gas to such zone, compressing 125

such charge of gas in the presence of such acid, and delivering such acid with the compressed gas.

4. The method described of treating gas by circulating sulphuric acid through the gas for absorbing moisture in the gas, consisting of delivering such acid to a compressor prior to its entrance to the compressing zone, sealing the stuffing-box of said compressor with such acid, transferring such acid to such zone after the transfer of the charge of gas to such zone, compress-

ing such charge of gas in the presence of such acid, and delivering such acid with the compressed gas, cooling such compressed gas 15 and acid, separating the latter from such compressed gas, and returning such cooled acid to said stuffing-box and compressor at a pressure greater than that of the gas to be compressed.

In testimony that I claim the invention above set forth I affix my signature.

LOUIS BLOCK.
